PROPORTIONING AND MIXING APPARATUS

Hartwig M. Hanson, Baltimore, Md., assignor to The C. M. Kemp Manufacturing Company, Baltimore, Md., a corporation of Maryland

Application March 25, 1954, Serial No. 418,737

6 Claims. (Cl. 48—184)

The present invention relates to an improved apparatus for the mixing of gases and is particularly adapted to the mixing of air and a combustible gas in the desired proportions.

To obtain a continuous flow and a completely combustible mixture of air and gas is very difficult. In mixing these gases, or air and gas, usually the air and gas are each under a constant pressure, or either or both may be under a predetermined vacuum after the mixing has taken place.

Numerous devices have been designed for this purpose as illustrated in the patent to W. W. Kemp et al., Nos. 1,771,223 and 1,880,141, and while these proportional mixers are satisfactory, there are occasions where a more accurate mixture is required, since the constituents of the gas not only vary, from time to time, but the carburetor is used with various gases. It is to obtain this more accurate mixture that the present improvement has been developed.

The primary object of the invention is to provide a proportional gas mixing apparatus in which the proportions of the several gases may be more precisely regulated.

Another object of the invention is to provide means without the device for making all the adjustment to all the flow control means.

A further object of the invention is to provide such an apparatus in a compact and economical design.

With these and other objects in view, the general principles of the invention are illustrated in the accompanying drawings and described in the detailed description that follows together with the manner in which the improved mixing apparatus is constructed, including its uses and advantages, in which:

Figure 1 is a top plan view of a carburetor involving this invention.

Figure 2 is a vertical sectional view taken along the line 2—2 of Figure 1.

Figure 3 is a horizontal sectional view taken along the line 3—3 of Figure 2.

Figure 4 is a horizontal sectional view taken along the line 4—4 of Figure 2.

Figure 5 is a vertical transverse sectional view taken along the line 5—5 of Figure 2.

Figure 6 is an enlarged fragmentary plan view of the improved mechanism for varying the extent of the opening of one of the gas ports.

Figures 7 is a sectional view taken along the line 7—7 of Figure 6.

In referring to the drawings like characters are used to designate like parts throughout the several views.

While the device is adapted to the proportionate mixing of many types of gases, its primary purpose is to mix air with the proper proportion of combustible gas for complete combustion and therefore the detailed description will follow generally its primary purpose.

The device is provided with a body portion, or casing 1 in which the interior is divided by partitions, or walls 2, 3 and 4 to provide independent air and gas chambers

2

5 and 6 and a mixing chamber 7. The chambers 5 and 6 are provided with inlets 8 and 9 respectively for admitting air and gas into the chamber. The chamber 7 is provided with an outlet 10 for conveying the mixture to its place of use. In order to conveniently assemble and service the device the casing is provided with a removable cover 11 having handles 12 and 13. The cover is fastened to the casing by a plurality of screws 14, to effect a tight seal as the cover member itself encloses part 10 of the mixing chamber 7. The casing is generally provided with a reinforced projecting ring as shown at 15, to which are fixedly secured to the stationary supports 16 and 17 upon which the device may rest.

The air and gas chamber dividing walls 2, 3 and 4 extend upwardly from the bottom of the casing to a plane passing horizontally through the upper half of the casing, as shown in Figures 2 and 5. Over the top of the two chambers 5 and 6 is a stationary top plate 18 in which a series of ports or rectangular-shaped apertures 19 are provided over the air chamber and a similar series of ports 20 are provided in the plate over the gas chamber. The top of the plate 18 is machined and polished throughout its entire upper area covering both the air and gas ports to provide a smooth flat surface. The mixing chamber occupies the remainder of the casing, extending over and around the air and gas chambers including the area over the plate 18 in order to receive the mixture of air and gas after they have passed through the ports.

30 For regulating the size of the ports, there is provided a movable or slideable plate 21. This plate is provided with a machined and polished under surface slidably receivable over the upper surface of the plate 18. In the movable plate 21 there are rectangular ports corresponding in size and shape with the ports mentioned in the plate 18 except, the ports in plate 21 are of such length as to cover both an air and corresponding gas port in the stationary plate 18. The plate 21 is generally referred to as a slide valve and is adapted to be moved back and forth over the stationary plate 18 to vary the size of the corresponding port openings. The size of the valve openings are gauged by the demand for the mixture which is reflected by the suction in the line leading from the mixing chamber through the outlet 10 or the differential in pressure in the air inlet and the mixture outlet.

To operate the slide valve there is provided a movable diaphragm member 22, having between its plates a diaphragm 23, which is located preferably adjacent the bottom of the mixing chamber and is subject at its bottom to the air inlet pressure. Connected with the member 22 is a stem 24. Hinged upon a pin 26 carried within the casing is a valve operating means. The valve operating means is provided with an integral horizontal arm 27 and a vertical arm 28 which extends upwardly from the pin 26. The arm 27 terminates adjacent the stem 24 and is connected therewith to move the swinging end of the arm up and down. The upper end of the vertical arm 28 is adapted to move the plate 21 over the ports as the member 24 is moved by the action of the diaphragm member 22. Attached to the upper end of the arms 28, are members 29 adapted to receive a bar 30 which is parallel with the pivot pin 26. Extending over the plate 21 and integral therewith along its lateral edges are a pair of bar members 31 and 32. These bar members have extended end portions 33 and 34 which also engage the bar 30. By this linkage, when the member 24 is moved downwardly by pressure upon the diaphragm member 22, the upper plate 21 will be moved over the stationary plate 18 in the direction of the arrow in Figure 2 and when the pressure is released the plate 21 will be moved in the opposite direction which will regulate the size of both air and gas ports simultaneously in

60 65 70 75 80 85 90 95

relation to the pressure present in the mixing chamber or the line connected therewith.

The sliding plate 21 is adjustable transversely of its normal reciprocating movement over the port openings by an adjusting screw 35. The screw 35 extends through the casing and is provided with a combination non-rotatable slide hollow threaded tube and head 36 in order that the tube may be longitudinally moved from outside the casing. The inner end of this tube is formed with a round head to operate within a bayonet type slot 37 formed within a member 38 fixedly secured to one of the lateral edges of the plate 21. This adjustment of the plate 21 is to relatively adjust the size of the respective air and gas ports and its purpose is similar to that for the adjustment shown and described in Patent No. 1,880,141.

It has been found that with the greater opening of the ports together, the gas proportional flow is slightly less, when all the ports are rectangles, and to compensate for this lessening of proportional gas flow, the end of one of the ports in plate 21, over the gas ports, is angled as shown at 38', to admit more gas as the ports are opened together by movement of plate 21.

In addition to the reciprocating adjustment and the lateral adjustment of the plate 21 for controlling simultaneously the size of all the port openings, there is a finer and more delicate adjustment in the size of one of the end gas ports as shown best in Figures 3 and 6. This gas port has an additional or extended area designated as 20' of any convenient shape, but shown herein as being of rectangular form. This particular area is adapted to be opened or closed by an independent auxiliary valve, which consists of an arcuate plate 39 having an open side 40, the plate having a depending pivoting bearing 39' held down by a screw 41. This plate is so arranged and of such thickness that the upper surface is in a plane with the upper surface of port plate 18, the plate 18 having an arc cut therefrom for plate 39 to rotate therein, in order that the plate 21 may slide over the auxiliary valve in its reciprocating movement over the surface of the valve plate 18.

This auxiliary arcuate valve plate 39 is operated from outside the casing by means of an internally threaded knurled wheel 42 which is rotatably mounted in a frame 43. Extending through bearings 44 and 45 in the frame 43 is a slideable threaded stem 46 fitting within the threaded knurled wheel 42. The frame 43 is secured about a suitable opening in the casing through which the inner end of the stem extends. The inner end of the stem 46 is provided with a bifurcated yoke 47 into which a link plate 48 is hinged. Secured to the plate 39 is an arm 49 with a projection 50 which is in turn hinged connected with the link plate 48. Link plate 48 has a bolt 51 therein moving in slot 52 in projection 50 to allow the straight movement of stem 46 to rotate projection 50 without binding.

By this arrangement the wheel 42 having a threaded aperture for the threaded stem 46 will move the slideable stem through the wheel and frame 43 when the wheel is rotated. Through the link connection with the arm 49, the arcuate plate 39 may be moved about its bearing 39'. As the arcuate plate 39 is rotated, the open side wall 40 of the plate is moved over the area portion 20' to regulate the size of the opening to vary the admission of gas therethrough. Plate 21 is suitably shaped to cover and uncover this auxiliary valve in its normal movements of reciprocation. The sidewise adjustment of plate 21 never uncovers the valve provided by plate 39, only the reciprocation of that plate uncovers this auxiliary valve.

The additional opening provided by valve plate 39 is of V shape, with the top of the V directed toward the body of plate 18, and in the direction of reciprocation of plate 21 in response to the demand for fuel, so that the further open the plate 39 is, the greater the flow of gas therethrough at full flow, or furthermost withdrawal from orifices 19, 20 of plate 18, that is, the direction and V

shape of the opening provided by rotating valve plate 39 gives greater flow at the far end of the reciprocation of plate 21.

When the correct mixture can not be made by the adjusting screw 35 which moves the plate 21 laterally over both series of ports to determine their respective sizes, it may be made by adjusting the arcuate valve 39 as previously described.

Having fully described the invention, it is to be understood that it is not to be limited to the detailed description of the preferred form illustrated herein, but the scope of the invention may be determined from the appended claims.

What is claimed as new and is desired to be secured by Letters Patent is:

1. In a gas and air mixing device, the combination of a gas tight closed partitioned casing having air, gas and mixing chambers therein, the casing having inlet openings leading through the casing wall and connecting with the respective air and gas chambers and having an outlet leading through the casing wall to the mixing chamber, an orificed flat cover plate extending over the outlet ends of said air and gas chambers, an orificed slide valve slide over said flat cover plate over the air and gas chambers, a diaphragm subjected to the pressure of the air and gas mixture in the mixing chamber, automatic valve operating means positioned within the casing having one end connected with said slide valve and the other end connected with said diaphragm whereby the slide valve will be slid over the orifices of the cover plate by movement of the diaphragm in response to the pressure of the air and gas in the mixing chamber to vary the size of all the air and gas orifices simultaneously and an auxiliary orifice closing valve in one of the gas orifices of said orificed cover plate for closing a portion of said gas orifice said portion being also covered and uncovered by said slide valve, means extending outwardly through the casing for adjusting the auxiliary valve independently of the action of the diaphragm and in cooperation with the slide valve operated thereby.
2. In a device as claimed in claim 1 in which one of the end gas orifices includes a small additional area in comparison to the remaining gas orifices with the auxiliary orifice closing valve positioned adjacent the orifice having the additional area for regulating the size of opening the additional area, the said valve being flush with the upper surface of the orifice containing cover plate.
3. In a device as claimed in claim 2 in which the auxiliary valve adjusting means includes a threaded stem threadedly engageable with a rotatable wheel outside the cover for operating the valve.
4. In a device as claimed in claim 1 in which the auxiliary valve is pivotally secured to the orifice cover plate and is adapted to swing over and close a predetermined area of an orifice in the cover plate.
5. In a gas and air mixing device, the combination of a tightly closed partitioned casing having air, gas and mixing chambers therein, the casing having inlet openings leading through the casing wall and connecting with the respective air and gas chambers and having an outlet leading through the casing wall to the mixing chamber, an orificed flat cover plate extending over the outlet ends of said air and gas chambers, an orificed slide valve slide over said flat cover plate over the air and gas chambers, means to reciprocally slide the slide valve to vary the flow of air and gas therethrough simultaneously, means to adjust the position of said slide valve to vary the proportions of air and gas flowing therethrough and an auxiliary orifice closing valve in one of the gas orifices of said orificed cover plate for closing a portion of said gas orifice said portion being also covered and uncovered by said slide valve, means extending outwardly through the casing for adjusting the auxiliary valve independently of the action of the slide valve and of the adjusting means.

6. In a gas and air mixing device, the combination of a tightly closed partitioned casing having air, gas and mixing chambers therein, the casing having inlet openings leading through the casing wall and collecting with the respective air and gas chambers and having an outlet leading through the casing wall to the mixing chamber, an orificed flat cover plate extending over the outlet ends of said air and gas chambers, an orificed slide valve slideable over said flat cover plate over the air and gas chambers, means to reciprocally slide the slide valve to vary the flow of air and gas therethrough simultaneously, and adjustable auxiliary valve means in one of the gas orifices of said orificed cover plate and flush with the slide valve, shaped to provide a substantially V-shaped orifice opening toward the slide valve and covered and uncovered 15

thereby in its reciprocation and extending in the direction of sliding of the slide valve adjacent the orifice cover plate over the gas chamber to provide an additional gas inlet area to the mixing chamber which increases in size both because of the withdrawal of the reciprocating plate in its reciprocation and of the direction and shape of the auxiliary valve orifice.
